DEVICE FOR COMPILING SALES AND
COLLECTION RECORDS

Elizabeth M. Graf, St. Louis, Mo.

Application July 29, 1931, Serial No. 553,703

9 Claims. (Cl. 129—16)

This invention relates to devices for compiling sales and collection records.

Objects of the invention are to provide a device for maintaining and supporting series of record sheets; to provide means for separating the series of record sheets into groups comprising a group for record sheets relating to purchases during a current month, a group of record sheets for those who have not made purchases during the month but who owe an account, and a group of record sheets of accounts which are dormant and inactive as to purchases and payments; and to provide an improved cabinet for receiving and containing the series of record sheets in proper relationship for convenient use.

Other objects will appear from the following description, reference being made to the annexed drawings, in which—

Fig. 1 is a perspective view showing my improved cabinet in open and extended form.

Fig. 2 is a vertical longitudinal sectional view of the cabinet showing three groups of record sheets therein.

Fig. 3 is a vertical transverse sectional view of the cabinet showing the manner in which the record sheets may be supported in extended position for convenient inspection.

Fig. 4 is a vertical longitudinal sectional view of the cabinet extended and without record sheets therein.

Fig. 5 is an enlarged detail sectional view approximately on the line 5—5 of Fig. 1.

Fig. 6 is a detail view showing the manner in which the detachable spacer is held in position in the cabinet.

Fig. 7 is a plan view of my improved record sheet.

Fig. 8 is a view showing another record sheet for receiving other records.

In the embodiment of the invention shown, my improved cabinet comprises a bottom wall 1 acting as a support, a vertical side wall 2 attached to and rising from one edge of the wall 1, a side wall 3 connected to the opposite edge of the bottom wall 1 by hinges 4, a front wall 5 extending transversely across the front of the wall 1 and connected therewith by hinges 6, and a back wall 7.

An arcuate arm 8 is attached to the front wall 5 and is formed with an arcuate slot 9. The wall 8 extends alongside of the inner surface of the wall 2. A projecting stud 10 secured to the wall 2 extends through the slot 9. The wall 5 may be swung outwardly a distance from the ends 55 of the walls 2 and 3, extent of such outward

movement being limited by the projection 10 engaging the end of the slot 9, as shown in Fig. 1.

A spring latch 11 is attached to the wall 3 and is formed with an angular portion 12 adapted to engage with a keeper member 13 attached to the wall 5 and thus support the wall 3 in a vertical position. Since the latch 11 is resilient, the wall 3 may be swung outwardly to open position while the wall 5 remains upright.

A pair of arms 14 are mounted for sliding movements in guides 15 attached to the upper side of the bottom wall 1 of the cabinet. These guides 15 have dovetailed grooves 16 in their lower sides and the arms 14 operate in said grooves. The rear ends of the arms 14 are attached to the lower marginal portion of the rear end wall 7 of the cabinet so that said rear end wall may be moved rearwardly from position against the wall 1 when it is desired to release the record sheets in a filled cabinet, or for any other purpose.

When the walls 3 and 5 are in their vertical positions and the wall 7 is against the rear end of the wall 1, a box-like cabinet is formed in which series of record sheets may be kept.

A rod 17 has its rear end rigid with the wall 7. Said rod projects forwardly into a tube 18 supported by the wall 2 by means of supporting clips 19. When the wall 7 is moved away from the wall 1, the arms 14 will support any cards or record sheets that move beyond the ends of the guides 15, and the rod 17 will limit extent of lateral movement of said cards or sheets so that said cards or sheets will thereby be supported approximately in alinement.

A wedge-shaped spacer member 20 is removably mounted in the cabinet, said spacer member being provided with notches in its lower edge receiving the guides 15. The spacer member may be hollow in order to reduce its weight to a minimum. One end of said spacer member is formed with a notch 21 (Fig. 6) adapted to receive the tube 18, and with a hook 22 adapted to extend between the tube 18 and the wall 2. Thus, the spacer member will be held upright. This construction permits the spacer member to be moved along the bottom of the cabinet from one position to another as required by the arrangement and readjustment of the record sheets or cards in the cabinet. This spacer is shown in Fig. 2 as separating one group of record sheets 23 from an adjacent group 24. The cabinet is shown as containing another group of record sheets 25 separated from the group 24 by a spacer device comprising finger 26 attached to the end of an arm 55

27 movably supported by the wall 2. The wall 2 has in its inner side a longitudinal slot 28 (Figs. 1 and 5) opening into a passage 29. The end of the arm 27 projects through the slot 28 and is formed with a head 30 mounted in the passage 29, and incapable of passing through the slot 28. Thus, the arm 27 is supported at a distance above the bottom and below the top of the cabinet and is capable of movement to different adjusted positions, as required by varying numbers of record sheets in the groups 24 and 25. The finger 26 extends between and separates the groups 24 and 25 so that, when the cabinet is opened, the operator can determine at a glance the approximate 15 location of any record sheet that may be needed. The operator determines immediately the exact group in which the record sheet is located because the groups are visually separated by the spacer 23 and the finger 26. The groups 24 and 20 25 incline upwardly and forwardly, due to the shape of the wedge spacer 20. The lower wall of the slot 28 is formed with notches 31 constituting abutments for the arm 27, so that the inclining group of record sheets 24 cannot push the arm 27 from its proper adjustment. The arm 27 may be 25 raised above the notches 31 and moved along the slot 28 to any position needed.

The wall 5 is formed with a hole 32 in alignment with a hole 33 through the spacer 20 and with a hole 34 in the wall 7. When the cabinet is closed, a rod 35 may be passed through the holes 32 and 33 and screwed into the hole 34, which is threaded for that purpose. A knob 36 on the front end of the rod 35 constitutes a handle whereby said rod may be operated and controlled.

The cabinet is provided with a lid adapted to cover the top of the cabinet and comprising a member 37 having marginal portions arranged to 40 seat upon the walls of the cabinet and having a depending portion 38 arranged to extend into the cabinet and thereby hold the lid from displacement.

As shown, the finger 26 is connected to the arm 27 by a pivot 39 which permits the finger to be turned to position in which it is entirely above the cards or sheets in the cabinet and then extended downwardly to position between the groups 24 and 25 of the cards or sheets.

50 My improved record card or sheet is preferably constructed and formed as shown in Fig. 7. The card or sheet is provided near its upper edge with a defined space 40 for the name of the salesman. A defined space 41 below the space 40 receives 55 the name of the customer, and a defined space 42 receives the customer's address. There are defined spaces 43, 44, 45 and 46 near the upper edge of the sheet or card for receiving symbols indicating information with respect to the payments to be made by the customer.

Below the designated spaces 41 and 42, the card or sheet is formed with a pair of spaced heavy-rule lines 47 and 48, leaving between them a defined space for receiving duplicated columnar 65 designations 49, 50, 51, 52, 53 and 54.

The columnar designations are separated by vertical lines 55 producing vertical columns 56, 57, 58, 59, 60 and 61. The spaces 49 to 54, inclusive, contain, respectively, the columnar designations "Month", "Monthly purchases", "Aging", "Past due balance", "Balance" and "Cash", and these designations, therefore, designate the respective columns 56 to 61, inclusive. Accordingly, I call these designations "Columnar designations".

A series of horizontal rule lines 62 extend across the sheet, crossing all of the columns thereon, thus forming spaces in each of the columns. In the column 56, the names of the months in which purchases are made are written by the operator; the total of monthly purchases are written in the column 57; the monthly payments are written in the columns 58; the past due balances for the respective months are written in the column 59; the total balance for the respective months is written in the column 60; and the amounts of cash payments made during the respective months are written in the column 61. This presents a very convenient assembly and arrangement of all of these essential records, so that the operator is informed at a glance as to the condition of any account. The lower portion of the sheet or card is formed with a defined space 63 for receiving any record of information or comments. The lower marginal portion of the card or sheet is formed with defined spaces 64 for receiving information connected with the account.

The lower marginal edge of this card or sheet is provided with notches 65 for receiving the 25 guides 15. These notches are separated by a downwardly extended portion 66 which extends between the guides 15 and is formed with a hole 67 that is thereby aligned with the holes 32, 33 and 34 so that, when the rod 35 is applied and as 30 shown in Fig. 2 of the drawings, said rod will pass through the holes 67 in all of these cards or sheets.

My invention also comprises the record card or sheet shown in Fig. 8. This card or sheet has 35 a vertical column 68 for receiving all surnames beginning with the same initial. For instance, all names beginning with "A", such as "Adams", "Arnold", and other names beginning with the letter "A", are written in the column 68 on lines 40 69. The lines 69 extend entirely across the sheet and across the "Monthly payment" columns 10, which receive records of monthly payments made by the respective customers whose names appear on corresponding lines 69. These cards shown 45 in Fig. 8 are not notched at their lower edges as are the cards illustrated in Fig. 7. These cards shown in Fig. 8 are slidable laterally from their positions in the groups of cards 23, 24 and 25, so that they may be readily removed. The cards shown in Fig. 8 may be colored in contrast with the colors of the cards shown in Fig. 7, or otherwise distinguished therefrom, so that there will be no difficulty in locating them. These cards are constructed so that they are freely movable 50 without obstruction by the guides 15, because it is necessary to remove them for record entries oftener than it is necessary to remove any one of the cards shown in Fig. 7. This is obviously true because each card shown in Fig. 7 is devoted 55 to a single customer, whereas the card shown in Fig. 8 contains the surnames of all customers whose names begin with the same initial.

Fig. 7 of the drawings indicates sufficiently the manner in which complete records of individual 65 customers' accounts are maintained and arranged. From an explanation of the specimen account shown on Fig. 7, it will be demonstrated clearly that the account is arranged in a more direct way than is possible by use of the usual 70 materials and appliances available for such uses. This invention eliminates a great deal of figuring and writing, usually required to derive the information contained in the complicated records of the type now used.

As shown in Fig. 7 of the drawings, an individual customer's account showed a balance of \$30.00 at the end of March, which appears in column 60. The designation "Mar" is written in alinement with "30.00" in column 56. There was no payment made during March by this customer and, since there was no balance due from the previous month, this "30.00", it will be seen, represents merchandise all purchased during 10 March. So, in column 57 for monthly purchases, the amount "30.00" is written.

At the close of books at the end of April, no purchases are shown; that is, the statement merely shows an old balance of \$30.00. On the 15 next line in Fig. 7, the designation "Apr" is written in column 56 and, in the column 59, showing past-due balance, "30.00" is written.

During May and June, the statements still show a balance of \$30.00, no further payments 20 or purchases having been made. At this time, it is not necessary to make an entry.

At the close of July business, the balance shown due is \$50.00, which is written in the next line 25 in column 60. As noted from the cash card, the payments total \$20.00 for July, and this "20.00" would be written in column 61. The designation "Jul" would, of course, be indicated in column 56. The last balance previous to the July balance shown in column 60 is \$30.00, and from this 30 amount the \$20.00 cash in column 61 is deducted, leaving a past-due balance of \$10.00, which is written in column 59. The purchases for July is the difference between \$10.00, past due balance in column 59, and \$50.00, the balance shown in 35 column 60, which is \$40.00. "40.00" is written in column 57.

The cash just posted is \$20.00 in column 61, and this amount is deducted from the oldest portion of the account, which is shown to be the 40 \$30.00 in March in column 57. This leaves a balance of \$10.00 due from March, and this amount "10.00" is written in the ageing column 58, in alinement with the "30.00" in March. The \$30.00 could be scratched but, in order not to deface the 45 column 57, it would be better to place a check mark behind the "30.00" to signify it had been paid, or partially paid.

At the end of August, the account shows a balance of \$60.00, which is written in column 60, 50 the designation "Aug" being indicated in column 56. The cash for August, as shown on cash card, is \$25.00, which is written in column 61. The balance previous to the new balance just written in column 60 was \$50.00. Deducting \$25.00 cash 55 in column 61, leaves a balance of \$25.00 past due, which is written in column 59. The monthly purchase is the difference between the balance "60.00" in column 60 and the past-due balance "25.00" in column 59, which is \$35.00, and this 60 "35.00" is indicated in column 57. The merchandise returns are automatically deducted from the monthly purchases. The \$25.00 cash in column 61 is deducted from the oldest portion. There is \$10.00 due from March in column 58, and this 65 \$10.00 is scratched, being taken care of by payment of \$25.00, the other \$15.00 being applied to the next oldest, which is \$40.00 from July. The \$40.00, being in the monthly purchase column 70 57, is not scratched, but a check mark is placed behind same, and the amount still due from July, which is \$25.00, is written in column 58 in alinement with "Jul".

To prove the record at the end of August after all of the above entries have been made, we find 75 in the ageing column 58, \$25.00 remaining from

July, and the monthly purchase following for August, \$35.00, or a total of \$60.00, the amount indicated as the balance in column 60.

At the end of September, this account as per statement shows a balance of \$50.00. This is 5 written in column 60. The cash for September as shown by the cash card is \$10.00, and this is written in column 61. Deducting the \$10.00 cash in column 61 from the preceding month's, or August, balance, \$60.00 in column 60, the difference, or now past-due balance, is \$50.00, which is written in column 59. Since the balance is \$50.00 in column 61 and the past-due balance is \$50.00 in column 60, the difference is .00 and shows no purchases have been made. For the 10 ageing of the account, the cash "10.00" in column 60 is deducted from the oldest part, which is \$25.00 in July, which leaves a balance of \$15.00 from July. The "25.00" is scratched and, in alinement with this figure and "Jul" in column 58, 15 "15.00" is written. Proof: July, \$15.00 plus August, \$35.00, is \$50.00, or the balance shown in 20 column 60.

When the books are closed at the end of 25 October, the account shows a balance of \$70.00, written in column 60 and, in alinement with this, "Oct" is written in column 56. The cash shown on the cash card is \$10.00, and this amount is written in column 61. Deducting the cash, "10.00" in column 61, from the old or September 30 balance, "50.00" in column 61, this leaves \$40.00, which is now past due, and this amount "40.00" is written in column 59. The difference between the balance "70.00" in column 60 and the past-due balance, "40.00" in column 59, is the monthly 35 purchase, which is \$30.00, and is written in column 57. The \$10.00 cash in column 61 is subtracted from the oldest part, which is \$15.00 in July, leaving \$5.00 due from July. The amount "15.00" is scratched out and "5.00" written in 40 column 59 in alinement with "Jul".

An extra column could be provided for ageing but, in almost all cases, two columns will be found sufficient.

Proof of record at the end of October as it now 45 stands: July, \$5.00; August, \$35.00 and October, \$30.00, a total of \$70.00, which is the balance indicated in column 60.

These records are continuously and successively 50 entered in the manner above described and, from said description, further and additional uses of the device will be readily understood. The names of the salesmen may be written or stamped in distinctive or contrasting colors in order to distinguish them from each other.

The manner of using the card shown in Fig. 8 55 will be understood from the description thereof already given. And the manner of locating the cards and the groups of cards within the cabinet is also clear.

When accounts become dormant, or where no balance is due and no purchase has been made during the month, the cards for such accounts may be kept in a separate file or toward the rear 60 of the cabinet, properly separated and distinguished from the remaining contents of the cabinet.

All other cards in the respective groups are 65 kept in alphabetical order, and the groups of cards may be distinguished by any appropriate 70 means or device.

In order to determine what payments were 75 made during any month, reference may be made to the cash card shown in Fig. 8, containing such records. These cards may be maintained with or

separate from the cards of Fig. 7, and afford reminders enabling the proper clerk or employee to determine easily wherein the past-due balances are shown.

- 5 Thus, the user of this invention is afforded an instant picture or vision of the condition of any accounts. The user may thus more easily obtain information of accounts that are past-due and keep collections closer to date. In connection 10 with each card, the customer's credit rating may be indicated in the space indicated, and the manner in which the account must be handled may be designated by checks in the spaces 43, 44 and 15 45, respectively, which are adjacent to the notations "C. O. D.", and "Special" and "Col", the significance of the first two designations being familiar, and the designation "Col" indicating that the account has been passed to a collector 20 for collection.
- 20 All of these advantages and uses are obtained by this compact and simplified invention without any inconvenience to the bookkeeper or ledger clerk, eliminating the necessity of turning and using heavy and bulky books and the desirability 25 for using a regular ledger. The entire record is kept in most convenient form.

I consider that this invention greatly facilitates the keeping of records of active and dormant accounts, presenting the entire condition of each 30 account so that the condition may be easily seen without leafing through different pages of a ledger or other record book. The cards may be formed and produced at comparatively nominal expense and thus made available to everyone having 35 need for information afforded by these cards.

The construction and arrangement of the invention may be varied within the scope of equivalent limits without departure from the nature and principle thereof. I do not restrict myself 40 in unessential particulars, but what I claim and desire to secure by Letters Patent is:—

1. A device of the character described comprising a support, walls connected with said support on three sides forming an enclosure open 45 at one end, a wall at said open end of said enclosure, guides for guiding said last named wall for movements toward and away from said first named walls, a series of cards mounted in said enclosure and having notches receiving said 50 guides, and devices mounted in said enclosure for separating said cards into groups.

2. A device of the character described comprising a support, walls connected with said support on three sides forming an enclosure open 55 at one end, a wall at said open end of said enclosure, guides for guiding said last named wall for movements toward and away from said first named walls, a series of cards mounted in said enclosure and having notches receiving said 60 guides, devices mounted in said enclosure for separating said cards into groups, and means for holding said devices in selected adjusted positions according to the requirements of the groups 65 of cards separated thereby.

3. A device of the character described comprising a support, walls connected with said support on three sides forming an enclosure open 70 at one end, a wall at said open end of said enclosure, guides for guiding said last named wall for sliding movements toward and from said first named walls, a series of cards mounted in said enclosure and having notches receiving said guides, an element mounted in said enclosure for separating said cards into groups, and a member 75 engaged with said element and with cer-

tain of said walls preventing withdrawal of said cards from said enclosure.

4. A device of the character described comprising a support, walls extending upwardly along the sides and ends of said support forming an enclosure open at the top, a series of cards mounted in said enclosure, a downwardly tapered member 5 mounted in said enclosure for separating said cards into groups and inclining adjacent groups of cards away from each other, and means other than said support and said walls engaging and supporting said member for forward and rearward movements in said enclosure.

5. A device of the character described comprising a support, side walls and end walls extending upwardly from the sides and ends respectively of said support and forming an enclosure open at the top, a series of cards mounted in said enclosure, a downwardly tapered member 10 in said enclosure separating said cards into 20 groups inclining away from each other, and means supported by one of said end walls and by one of said side walls respectively for supporting said member in position to separate said cards into groups inclining away from each other. 25

6. A device of the character described comprising a support, walls extending upwardly from the sides and ends of said support and forming an enclosure open at the top, a series of cards mounted in said enclosure, a downwardly tapered member 30 in said enclosure separating said cards into 35 groups inclining away from each other, means for supporting said member in position to separate said cards into groups inclining away from each other, means for preventing withdrawal of 35 said cards from said enclosure, an additional series of cards mounted in said enclosure, and a device for separating said additional series of cards from said first series of cards. 40

7. A device of the character described comprising a support, side walls and end walls connected with the sides and ends respectively of said support and forming an enclosure open at the top, a series of cards supported on the bottom of said enclosure, a downwardly tapered member 45 mounted in said enclosure on said support separating said series of cards into groups and inclining one of said groups away from the other while said cards remain supported on the bottom of said enclosure, means other than said cards for holding said member in upright position between said groups of cards, an additional series of cards mounted in said enclosure adjacent to one of said groups of cards, and a device supported in said enclosure by one of said side walls and separating said additional series of cards from the adjacent group of said first series and supporting the upper end of said adjacent group of cards. 50

8. A device of the character described comprising a support, side walls and end walls connected with said support and forming an enclosure, a series of cards mounted on said support, a downwardly tapered member mounted on and movable along said support in said enclosure to 65 different positions to separate said cards into selected groups and to incline said groups of cards away from each other while all of said cards remain on said support, means other than said cards for holding said member in upright position, and an element in said enclosure for supporting the upper ends of one of said groups of cards. 70

9. A device of the character described comprising a support, side walls and end walls con- 75

5 nected with said support and forming an enclosure, a series of cards mounted on said support, a downwardly tapered member mounted on and movable along said support in said enclosure to different positions to separate said cards into selected groups and to incline said groups of cards away from each other while all of said cards remain on said support, means

other than said cards for holding said member in upright position, an element in said enclosure dividing one of said groups of cards into two sub-groups and supporting one of said sub-groups in inclined position, and a device supported by one of said side walls for supporting said element. 5

ELIZABETH M. GRAF.
